(57) **CLAIM**

The ornamental design for a tabletop base for a button panel, as shown and described.

DESCRIPTION

FIG. 1 shows a front perspective view of a tabletop base for a button panel.

FIG. 2 shows a rear perspective view thereof.

FIG. 3 shows a top plan view thereof.

FIG. 4 shows a bottom plan view thereof.

FIG. 5 shows a front view thereof.

FIG. 6 shows a rear view thereof.

FIG. 7 shows a right side view thereof.

FIG. 8 shows a left side view thereof; and,

FIG. 9 shows a front perspective view thereof shown in an alternative environment of use.

The broken lines showing portions of the tabletop base for a button panel are included to show unclaimed subject matter only and forms no part of the claimed design.

1 Claim, 7 Drawing Sheets
